CASING SUSPENSION HEAD

Dennis L. Driscoll, South Gate, Calif., assignor
to Lawrence F. Baash, Los Angeles, Calif.

Application June 13, 1938, Serial No. 213,434

4 Claims. (Cl. 285—22)

This invention relates to well equipment and relates more particularly to casing heads for suspending the casings of wells, such as oil wells and gas wells. A general object of this invention is to provide a casing head that is simple and inexpensive, and that materially facilitates the dependable suspension of the casings of a well.

Another object of this invention is to provide a casing head embodying suspension members or sections adapted to be welded to the strings of casing while the same are maintained under tension by the hoisting equipment, or otherwise, to support or suspend the casing strings and maintain the tension thereon following the disassociation of the hoisting equipment from them and following the cutting off of the upper portions of the casings.

Another object of this invention is to provide a casing head of the character mentioned embodying means for independently suspending a plurality of strings of casing.

An important object of this invention is to provide a casing head of the character mentioned in which the welds between the casing strings and the suspension sections are relieved of or protected against the fatiguing and breaking vibrations of the casings to dependably support the casing strings indefinitely.

Another object of this invention is to provide a casing head of the character mentioned in which the welds between the casing strings and their respective suspension members serve to seal off or pack off between the casings and the members, thereby eliminating the necessity for packing at these points and assuring positive, dependable seals.

Another object of this invention is to provide a casing head that is compact and short and capable of being installed in the well derrick cellar so that all of its connections may be installed below the derrick floor.

Another object of this invention is to provide a casing head in which vertically spaced welds are provided between each casing string and its suspension section or member and extensive engagement is provided between each casing and its suspension member assuring strong positive vibration resisting connections.

Another object of this invention is to provide a casing head of the character mentioned that embodies novel means for suspending the inner casing string or tubing.

A further object of this invention is to provide a casing head that may be easily and quickly installed.

The various objects and features of my invention will be fully understood from the following detailed description of typical preferred forms and applications of the invention, throughout which description reference is made to the accompanying drawing, in which:

Fig. 1 is a central vertical sectional view of the improved casing head provided by this invention. Fig. 2 is an enlarged fragmentary horizontal detailed sectional view taken as indicated by line 10 2—2 on Fig. 1. Fig. 3 is an enlarged fragmentary horizontal sectional view taken as indicated by line 3—3 on Fig. 1. Fig. 4 is a fragmentary side elevation of the casing head of the present invention with a portion broken away to appear 15 in vertical cross section illustrating a slightly modified form of connecting means or welding means, and Fig. 5 is an enlarged fragmentary horizontal detailed sectional view taken as indicated by line 5—5 on Fig. 4.

The casing head of the present invention is capable of embodiment in forms for carrying or suspending any number of strings of well casing or tubing. In the drawing I have shown the head employed in connection with a surface string or outer casing string 10, a second string of casing 11 and a third or inner string 12 of casing or tubing. It is to be understood that the particular application of the invention illustrated in the drawing is not to be construed as limiting or restricting the scope of the invention.

The form of the invention illustrated in Figs. 1, 2 and 3 of the drawing may be said to comprise, generally, a base section 14, means 15 for securing the surface string 10 to the base section 14, a suspension member or section 16 on the base section 14, means 17 for securing the casing string 11 to the section 16, an upper suspension section 18, and means 19 for securing the third string 12 to the section 18.

The base section 14 forms the casing head section or member for the surface string or outer casing string 10 and supports the other suspension members or sections 16 and 18 of the head. The base section 14 is an upright tubular member 45 having a central vertical opening 20. A radially projecting flange 21 of substantial width is provided on the lower end of the section 14 and is adapted to rest or bear on a suitable support to carry the head. In practice the base flange 21 50 may rest on a support at the floor of the derrick cellar. A radially projecting flange 22 is provided on the upper end portion of the base section 14. The upper surface of the flange 22 is preferably substantially horizontal. Reinforcing 55

webs 23 may be provided on the section 14 and may extend between its flanges 21 and 22 to strengthen the section. The opening 20 of the base section 14 is provided to receive the casing string 10. It is a feature of the invention that the opening 14 is of substantial length or vertical extent and accurately or closely receives the casing string 10 so that its wall has extensive cooperation with the surface of the casing string to absorb or eliminate vibration of the casing. The opening 20 is of uniform diameter so that its wall cooperates with the external surface of the casing string throughout the vertical extent of the base section 14. The wall thickness of the section 14 at a point or zone adjacent its flange 21 is preferably reduced for purposes which will become evident.

The means 15 for securing the surface string or outer casing string 10 to the base section 14 is in the nature of a welding means or welded connecting means. The upper end of the casing string 10 is preferably cut off substantially flush with the upper end of the section 14 and the means 15 includes an annular weld 24 connecting or joining the upper end portions of the section 14 and the casing string 10. It may be preferred to bevel or flare the upper end position of the opening 20 to receive the weld 24. The upper surface of the weld 24 is preferably about flush with the upper surface of the section 14. In the preferred construction the weld 24 is continuous or annular to form a closure or seal about the casing string 10, if a seal is required at this point.

The means 15 further includes welds joining the casing string 10 to the section 14 at a point or plane below the weld 24. A series or row of circumferentially spaced openings or windows 25 is formed in the wall of the section 14. It is preferred to provide the windows 25 in the wall portion of the section 14 of reduced thickness and to locate them in spaced adjacent relation to the base flange 21 to be a substantial distance below the weld 24. Welds 26 are made or provided in the windows 25 to connect or join the walls of the windows and the periphery of the casing string 10. There is preferably a large number of windows 25 of substantial size so that the welds 26 may be numerous and of substantial extent. The windows 25 are located and proportioned to facilitate the ready provision or formation of the welds 26. It will be understood how the vertically spaced weld 24 and welds 26 serve to securely and dependably connect the casing string 10 with the base section 14. It is to be particularly noted that the extensive engagement of the external surface of the casing string 10 with the wall of the opening 20 prevents relative vibration between the casing string and the base section 14 and thus protects the welds 24 and 26 against the fatiguing and breaking effects of such vibration. The extensive engagement of the casing string 10 with the wall of the opening 20 is at or immediately adjacent the spaced welds 24 and 26 eliminating any vibration or flexing of the casing string 10 relative to the section 14 that might otherwise impose strains on the welds 24 and 26. Ports and pipes are provided to take off gas and fluid from the casing string 10 and, if necessary to introduce fluid to the casing string 10 to kill the well, etc. Threaded ports 27 are provided in the wall of the base section 14. The ports 27 are spaced between the windows 25 and the flange 22 and extend inwardly to join the opening 20. Following the attachment of the base suspension section 14 to the casing string 10 openings 28 are

cut or drilled in the wall of the casing string to register with the ports 27. Pipes 29 extend from the ports 27 and communicate with the interior of the casing 10 for the purposes mentioned above.

The suspension member or section 16 rests on or is carried by the base section 14 and is provided to suspend the casing string 11. The section 16 is a tubular spool-like element intended to be arranged on the section 14 when the casing string 11 is in condition for landing or suspending. An outwardly projecting radial flange 30 is provided on the lower end of the section 16 to oppose the flange 22 of the section 14. It is preferred to provide packing means or sealing means 18 between the flanges 22 and 30. An annular groove 31 is provided in the upper side of the flange 22 and carries suitable packing 32. An annular bead or tongue 33 projects from the under side of the flange 30 and enters the groove 31 to compress the packing 32. It will be observed that the packing means just described is at the upper end of the section 14 and is conveniently accessible. Bolts 34 are passed through aligned openings in the flanges 22 and 30 to secure the section 16 to the base section 14. An annular outwardly projecting flange 35 is provided on the upper end of the section 16. Reinforcing webs 36 may be provided on the section 16 and may extend between its flanges 30 and 35.

The central longitudinal opening 37 of the section 16 is co-axial with the opening 20 and is provided to pass or receive the casing string 11. In accordance with the invention the opening 37 is proportioned to closely or accurately receive the casing string 11 so that its wall has extensive engagement with the casing. This engagement is such that it prevents vibration of the casing string 11 relative to the head section 16.

The means 17 serves to secure or connect the casing string 11 to the section 16 to be suspended therefrom. The means 17 is similar to the means 15 described above. In accordance with the invention the means 17 includes a weld 38 securing the upper end of the casing string 11 to the section 16. The weld 38 occurs at the mouth or upper end of the opening 37 and is preferably annular or continuous to form a fluid shut-off or seal about the upper end of the string. Thus the weld 38 makes it unnecessary to employ other packing means for sealing between the casing string 11 and the section 16. The upper portion of the opening 37 may be flared or enlarged to receive the weld 38.

The means 17 further includes welds connecting the casing string 11 with the section 16 below the weld 38. A row or series of circumferentially spaced lateral openings or windows 39 is provided in the wall of the tubular section 16. The windows 39 are spaced between the upper and lower ends of the section 16 and are preferably spaced a substantial distance below the weld 38. Welds 40 are provided or formed in the windows 39 to assist in securing the casing string 11 to the section 16. There is preferably a large number of windows 39 of substantial size so that an ample number of welds 40 of ample size may be formed. The weld 38 and the welds 40 securely and dependably attach the casing string 11 to the section 16. It is to be observed that the weld 38 and the welds 40 are at or adjacent the extensive area of engagement of the casing string 11 with the wall of the opening 37. The engagement of the casing 11 with the wall of the opening 37 prevents vibration and flexure of the casing string relative to the section 16.

to the section 16 and thus prevents such vibrations and flexure from fatiguing and breaking the welds 38 and 40.

The section 16 is preferably ported to permit the escape of gas and fluid from the casing string 10 and to provide for the introduction of fluid to the casing string 10. Ports 41 are provided in the wall of the section 16 in a plane below the windows 39 and pipes 42 extend outwardly from the ports 41. The opening 37 of the section 16 has grooves 41a extending downwardly from the ports 41 to the lower end of the section or the opening 37 to maintain the ports 41 in communication with the upper end of the casing string 10.

The suspending section 18 is the upper section of the head. It is to be understood that where the well has more casing strings than shown in the drawing, sections similar to the suspending section 16 may be stacked one upon the other with the lowermost section on the section 16 for the purpose of suspending the additional casing strings. The section 18, or a section of similar construction but of different dimensions, is arranged on the uppermost welded-on suspension section. In the case illustrated in the drawing the section 18 is supported on the upper welded-on section 16 to suspend the innermost string or tubing string 12.

The section 18 is a tubular cap-like member provided at its lower end with a radially projecting flange 44. Bolts 45 are passed through openings in the flanges 35 and 44 to secure the section 18 to the section 16. Packing means is provided to seal between the sections 16 and 18. This packing means includes a groove 46 formed in the upper side of the flange 35 and carrying packing 47. It will be observed that the packing means between the sections 16 and 18 occurs at the upper end of the section 16 where it is readily accessible. The section 18 extends upwardly from its flange 44 and its upper end portion is reduced in diameter. In accordance with the invention this reduced upper end portion of the section 18 is internally and externally threaded to receive a nipple or tube 49. In the typical case illustrated the tube 49 is threaded in the reduced upper portion of the section 18. Ports 50 are provided in the wall of the section 18 above its flange 44 and pipes 51 extend outwardly from the ports 50. Gas or fluid from the casing string 11 may escape through the pipes 51 and the pipes 51 may be employed to introduce fluid to the casing string 11.

The means 19 serves to suspend the innermost string or tubing string 12 from the section 18. The means 19 includes a depending tubular flange 52 on the interior of the section 18. The internal diameter of the flange 52 may be substantially the same as that of the reduced upper portion of the section 18. The flange 52 is spaced inwardly from the surrounding wall of the section 18 to leave an annular groove placing the pipes 51 in communication with the upper end of the casing string 11. The means further includes a sleeve or nipple 53 threaded into the flange 52. The upper portion of the nipple 53 is preferably thick-walled or heavy. The lower portion of the nipple 53 is reduced in external diameter and is adapted to be threaded in a collar 54 on the upper end of the tubing string 12. It will be apparent how the nipple 53 serves to connect the string 12 with the section 18 to be suspended therefrom. The nipple 53 forms a somewhat flexible connection between the string 12 and the

section 18 and prevents the tubing from breaking off or from being subjected to strains in the event that there is a slight misalignment of the tubing string.

Figs. 4 and 5 of the drawing illustrate a slightly modified means for securing or suspending a casing string 60 from a section 16a of the casing head. It may be assumed that the member or section 16a illustrated in the drawing supports an inner or intermediate casing string 60 and occupies a position in the head similar to that of the section 16 described above. The section 16a may be similar in shape and construction to the above described section 16 being a tubular member provided with a central vertical opening 37a and having a projecting base flange 30a and a radially projecting top flange 35a. Bolts 34a may secure the section 16a to the casing head section on which it rests.

The means for securing the casing string 60 to the section 16a comprises a weld 61 securing the upper end of the casing string 60 to the upper end portion of the section 16a. The weld 61 is preferably annular or continuous to form a fluid-tight seal between the casing string and the section 16a. The means for securing the string 60 to the section 16a further includes an annular groove 62 formed in the wall of the opening 37a. Circumferentially spaced ports or windows 63 extend outwardly from the groove 60 to the exterior of the section 16a. An annular or continuous weld 64 is provided in the groove 62 to assist in securing the casing string 60 to the section 16a. The ports or windows 63 make the groove 62 accessible from the exterior of the section 16a and facilitate the provision or formation of the weld 64. The windows 63 make it possible to provide a continuous or annular weld 64 which may form a fluid seal about the casing string 60. The opening 37a closely receives the casing string 60 and the casing has extensive engagement with the wall of the opening. This engagement prevents vibration of the casing string 60 and fatiguing and breaking of the welds 61 and 64. The weld 64 is spaced below the weld 61 and occurs between the ends of the area of engagement between the casing string 60 and the wall of the opening 37a.

It is believed that the practicability and utility of the improved casing head provided by the invention will be readily understood from the foregoing detailed description. Referring now to Figs. 1, 2 and 3, the lower section 14 may be readily arranged about the upper end of the surface string 10 when the same has been cemented in the usual manner. The weld 24 and welds 26 may be easily and quickly made to secure the casing string 10 to the base section 14 and to provide a fluid tight seal about the string 10. Following the deepening of the well and the setting and cementing of the casing string 11 the section 16 may be arranged about the string 11 and lowered to its position on the section 14. In accordance with the usual practice the string 11 may be put under tension or stretched and maintained in this condition throughout the cementing process. An additional stretch or strain is placed on the string 11 and the string is secured to the section 16 and is maintained while the welds 38 and 40 are formed. The hoisting equipment of the derrick or any other suitable means may be employed to maintain the section 11 under tension prior to and during its connection to the section 16. In accordance with the invention the welds 40 and, if desired, the weld 38, may be made prior to the cutting off of the upper portion of the casing 75.

string 11. In other words, the string 11 may be secured to or welded to the section 16 before its upper end part is cut off. Following the welding of the casing string 11 to the section 16 and 5 when the welds 38 and 40 have cooled, the means employed to maintain the tension on the string may be disconnected from it and the string 11 may be cut off adjacent the plane of the upper end of the section 16. The welds 38 and 40 10 securely attach the casing string 11 to the section 16 to suspend the string and to maintain the stretch or tension in it. When it becomes desirable or necessary to suspend the string 12 the tubing string 12 is connected with the section 18 by 15 the nipple 53 and the section is lowered to its position on the section 16. When the bolts 45 have been arranged in place the assembly is complete.

It is to be noted that the casing head provided by the present invention does not embody packing 20 means for sealing between the casing strings and the head sections that is subject to deterioration and that requires reconditioning. The welds securing the casing strings to the head sections are fully protected against vibration and, therefore, 25 are not subject to failure. The head is compact and short and, therefore, is suitable for installation in the derrick cellar. The various parts of the head are simple and inexpensive to manufacture, and are convenient to install.

30 Having described only typical preferred forms and applications of my invention, I do not wish to be limited or restricted to the specific details herein set forth, but wish to reserve to myself any variations or modifications that may appear 35 to those skilled in the art or fall within the scope of the following claims:

Having described my invention, I claim:

1. In a casing head for suspending a well casing, a member having an opening receiving the 40 casing, an annular groove in the wall of the opening and lateral windows joining the groove to make the same accessible from the exterior of the

member, and an annular weld in the groove securing the casing to the member, the size and spacing of said windows allowing the ready formation of said annular weld.

2. In a casing head for suspending a well casing, a section having an opening receiving the casing, vertically spaced welds securing the casing to the section, the opening being proportioned so that its wall has extensive cooperation with the casing to protect the welds against vibration 10 of the casing, the casing having a lateral port between the vertically spaced welds and the section having a lateral port registering with the port in the casing, and a pipe extending from the port in the section. 15

3. In a casing head for suspending a well casing, a suspension section having a vertical opening receiving the casing, the opening being proportioned to have an extensive portion of its wall in engagement with the casing, vertically spaced 20 welds securing the casing to the section at said wall portion of the opening, at least one of said welds being annular to form a seal between the section and casing, the casing and section having lateral ports spaced between said vertically spaced 25 welds, and a fluid connection for the port in the casing whereby fluid may be introduced into the casing.

4. In a casing head for suspending a well casing, a member having an opening receiving the casing, an annular groove in the wall of the opening and lateral windows joining the groove to make the same accessible from the exterior of the member, an annular weld between the upper end 30 of the member and section, an annular weld in the groove securing the casing to the member, the size and spacing of the windows allowing the ready formation of the last named weld, the member and casing having registering lateral 35 ports spaced between said annular welds, and a pipe extending from the port in the member. 40

DENNIS L. DRISCOLL.
